UNITED STATES PATENT OFFICE.

ARTHUR ERNEST HEATH, OF LONDON, ENGLAND.

SPARKING PLUG FOR IGNITION PURPOSES.

1,343,052.

Specification of Letters Patent.

Patented June 8, 1920.

Application filed September 29, 1919. Serial No. 327,015.

To all whom it may concern:

Be it known that I, ARTHUR ERNEST HEATH, a subject of the King of Great Britain, residing at London, England, have invented certain new and useful Improvements in Sparking Plugs for Ignition Purposes, of which the following is a specification.

The object of this invention is to give further protection to the insulator together with the central electrode, from the hot gases and oil vapor, than is possible with known sparking plugs having baffles of various forms, and to prevent as far as possible the insulator being overheated and breaking down electrically, the carbonizing of its surface and preignition.

For the purpose of my invention I position a sleeve of metal or other suitable material in combination with a holed baffle such sleeve being positioned between the insulator carrying the central electrode and the inner wall of the sparking plug body at that part exposed to the hot gases such sleeve being held in position by any desired means such as by forming the sleeve with a flange and gripping the flange on a shoulder formed on the plug body by the nut retaining the insulator. On each side of the sleeve is a space and below the sleeve is positioned the baffle through which I drill a ring of holes, such holes being so positioned that the bulk of the hot gases and oil vapor are directed into the space between the sleeve and the plug body and the sleeve may be contracted at the lower part to assist in directing the gases and oil vapor into the space between the sleeve and the plug body, a small portion of gases and oil vapors also passing through the hole in the center of the baffle mixing with the cooler gases that have passed through the ring of holes in the baffle and toward and into the space between the sleeve and the insulator.

The tubular sleeve may be held in the plug body in several ways and be made in several forms, for instance it may be held at its top by a flange or collar and around its circumference and near its lower end by a flange or collar having slots for the passage of gas and oil vapor into the outer space.

My invention will be clearly understood

from the following description aided by the example shown on the annexed drawings. 55

Figure 1 is a part sectional elevation of a sparking plug embodying my invention.

Fig. 2 is an under plan of Fig. 1.

Fig. 3 is a plan of the sleeve.

Fig. 4 is an elevation of the sleeve. 60

Fig. 5 is an under plan of the sleeve.

I provide the plug body A with a shoulder B and with a baffle C having holes D. Within the plug body A, I position a sleeve E such sleeve having a flange F engaging the shoulder B and its body portion somewhat conical or to conform somewhat to the shape of the insulator G at the part which it surrounds, the sleeve further having a collar or flange H on its outer surface 70 and near its lower end such collar being provided with slots or openings I to allow free access of the gases and oil vapors to the space between the sleeve and the wall of the plug A the collar or flange making metallic contact with the plug body A so as to assist in holding the sleeve E in place and conveying the heat of the gases imparted to the sleeve as much as possible to the plug body. The sleeve E is contracted 75 at the lower part as at J to assist in conducting the gases entering by the holes D into the space between the sleeve E and the plug body A the holes D being also positioned for that purpose. 80

The end of the central electrode K is situate within the central hole of the baffle as is usual and the sleeve E is so constructed that there is a space on each side of it, that is to say, there is a space between the sleeve 90 and the wall of the plug as also a space between the sleeve and that part of the insulator exposed to the hot gases. 85

By this construction the main portion of the hot gases will pass through the holes D 95 into the space between the sleeve and the plug body and thus the bulk of the heat will be imparted to the sleeve and plug body and not direct to the insulator G, there only being a small proportion of the hot gases 100 passing through the hole surrounding the electrode these gases mixing with the gases that have been cooled by passing through the holes in the baffle and as a great proportion of the heat of these will be imparted 105 to the holed baffle C and the sleeve E the

sleeve E having contact with the plug body by its flanges and collar F and H the heat will be conveyed to the plug body and thereby the insulator G and electrode K are kept 5 as cool as possible.

The sleeve E is further held in position by the shoulder portion L of the insulator pressing upon its flange F when the gland nut M is screwed home or the flange F may 10 be dispensed with, a washer N being interposed between the shouldered portion L and the flange F or edge of the sleeve E and the shoulder O, thus making a gas tight joint.

What I do claim as my invention and 15 desire to secure by Letters Patent is:—

1. In sparking plugs for ignition purposes having a baffle provided with a ring of holes, a tubular sleeve positioned and held within the plug body and surrounding 20 the insulator carrying the central electrode at that part exposed to the hot gases, a space being provided on each side of the sleeve, substantially as and for the purposes set forth.

25 2. In sparking plugs for ignition pur-

poses having a baffle provided with a ring of holes, and a tubular sleeve as set forth in claim 1 positioning the holes in the baffle so as to direct the hot gases passing through same into the space between the sleeve and 30 the plug body.

3. In a sparking plug for ignition purposes having a baffle provided with a ring of holes, a tubular sleeve within the plug body and surrounding the insulator of the 35 central electrode at the part exposed to the hot gases and having spaces on each side, such sleeve being provided with flanges for engagement and contact with the plug body for conducting the heat imparted to it by 40 the hot gases away from the insulator and to the plug body, substantially as described.

In testimony whereof I have hereunto set my hand in presence of two subscribing witnesses.

ARTHUR ERNEST HEATH.
